UNITED STATES PATENT OFFICE.

CHARLES J. JOLIDON, OF HARTFORD, CONNECTICUT.

FIREARM.

1,310,397.

Specification of Letters Patent. Patented July 15, 1919.

Application filed July 9, 1914. Serial No. 849,965.

To all whom it may concern:

Be it known that I, CHARLES J. JOLIDON, a citizen of the United States, residing in Hartford, in the county of Hartford and 5 State of Connecticut, have invented a new and Improved Firearm, of which the following is a specification.

My invention relates more especially to that class of firearms in which the loading, 10 ejection of shells, &c., is performed automatically, as by making use of the force of the exploding gases, and an object of my invention, among others, is to provide a firearm of this class having means for insuring that the projectile shall have passed 15 out of the muzzle before any opening movement of the breech shall occur, and to otherwise improve the action of the breech opening mechanism.

20 One form of device embodying my invention, and in the construction and use of which the objects herein set out, as well as others, may be attained, is illustrated in the accompanying drawings, in which—

25 Figure 1 is a side view of a pistol embodying my invention.

Fig. 2 is an end view looking toward the muzzle, the lower part of the handle being broken away.

30 Fig. 3 is a detail bottom view of the barrel and sliding case and breech bolt.

Fig. 4 is a detail view of the upper back part of the pistol, with parts broken away to show construction.

35 Fig. 5 is a view in section through the same on plane denoted by dotted line 5—5 of Fig. 4.

My invention relates particularly to the means for releasing the breech opening 40 mechanism to permit backward movement of the case, and also to the means for tensioning the hammer spring, and I have, therefore, illustrated in the drawings herein, only so much of the mechanism as directly 45 relates to these parts, it being understood that the mechanism not specifically illustrated may be of any well known and approved form of construction.

In the accompanying drawings the number 50 7 denotes the handle, 8 the trigger guard, 9 the trigger, and 10 the receiver of my improved pistol, all of which may be of any approved form of construction.

It is a well known fact that when a fire- 55 arm, and more especially one that is held in the hand and discharged without other sup-

port, is subject to reaction, such that the hand or support is thrown upward to a decided degree and with considerable force. This reaction causes an upward movement of 60 the hand to take place after the bullet has passed out at the front end of the muzzle, and it is the purpose of my present invention to utilize this force to unlock the mechanism for opening the breech-bolt, thus insuring that this mechanism shall not be unlocked until the bullet has been forced out at the muzzle.

In the structure illustrated herein and embodying this idea the barrel 11 is pivotally attached to the receiver as at 12, and a spring 13, located forward of the pivot 12, tends to hold the rear end of the barrel at the lowermost limit of its play. It will be noted that this construction causes the rear 70 end of the barrel to swing upward, that is, in a direction away from the trigger, from its normal position to unlock the case. This rear end is provided with stops 14 that are projections formed to engage shoulders 15 80 on lips 16 projecting from the side parts of the case and breech bolt 17 to hold the latter against backward movement. It will be understood that the case is suitably connected with spring actuated mechanism for holding 85 it in its closed or forward position and for moving it to this position when other forces which have moved it backwardly have been expended or neutralized, any of the well known mechanisms for accomplishing this result being suitable for the purpose.

The case 17 is so constructed as to embody the breech bolt, and as it is moved backward, it forces the hammer 18 to its 95 cocked position, and in order to reduce the resistance to this backward movement of the case and breech bolt to a minimum degree so that as little force as possible of the exploded gases will be required to effect its 100 opening movement, I have provided means for neutralizing the force of the hammer spring during such opening movement, as it will be apparent that when the bullet has left the barrel the forces of the exploded 105 gases that may be utilized for opening the breech will have been reduced to a material degree. In the mechanism illustrated herein and embodying this invention a hammer supporting pin 19 is located in the receiver 110 10 and passes through the hammer, projecting on opposite sides thereof and forming

the pivotal support therefor. The hammer is preferably recessed on one side as at 20 and a helical spring 21 is located in this recess, one end 22 of the spring being engaged in an opening in the hammer and the opposite end 23 being located in a slot 24 in the pin. This spring 21 acts to throw the hammer forward to explode a cartridge, and a tensioning lever 25 is secured to the 10 end of the pin in such manner that the degree of tension upon the spring may be varied at will. In the form of construction herein shown the end 26 of the pin is of angular form in cross section to receive an 15 opening of similar form in the end of the lever 25. This lever has a slot 30 that receives a pin 27 removably engaging an opening 28 in the case 17. The pin 27 is secured to the lever 25 in any suitable manner to 20 permit movement of the pin along the slot as the lever is swung on its pivot and the spring action of the lever may be sufficient to enable the pin to be disengaged from the opening 28 and engaged within an opening 25 29 in the handle 7. It will be understood that other means for removably securing the lever to the frame or handle may be employed, and the invention is not limited to any specific means for accomplishing this 30 result. The tension upon the hammer spring may be such that when the lever 25 is swung to its lowermost position, with the pin 27 engaging the opening 29, there will be no force exerted upon the hammer, even should 35 the latter be moved to its cocked position, and this arrangement thus provides a safety device by removing the tension of the hammer spring so that it cannot operate the hammer.

40 In the operation of the device the reacting force of the exploding gases will so act upon the hand of the person firing the pistol that the stop 14 will be disengaged from the catch formed by the shoulder 15 and lip 16, and the barrel 11 will be so 45 pivotally mounted that this reacting force will disengage these parts permitting the case and breech bolt 17 to be forced backward, and the spring 13 will be arranged 50 to act in opposition to this disengaging force. Upon the release of the case 17 the force of the exploding gases will throw the case and breech bolt backward, forcing the hammer 18 to its cocked position and swinging 55 the lever 25 on its pivot. This swinging movement of the lever 25 will rotate the pin 19 and this maintains the tension of the spring 21, which tension is therefore not increased as the hammer is moved backward, 60 and there is therefore no increased resistance imposed to the backward movement of the case and breech bolt caused by the hammer spring. When the shell has been ejected, the case and breech bolt 17 is moved forward 65 to its closed position carrying with it the lever 25 and placing sufficient tension upon the spring 21 to effect its purpose in forcing the hammer forward to explode the cartridge. Whenever the word "case" is used herein it will be understood to include the 70 breech-bolt that is shown herein as a part of the case.

75 While I have shown and described herein one form of mechanism for accomplishing the purposes of my invention, it will be understood that this purpose may be effected with mechanism differently constructed, and I do not therefore limit the invention to its embodiment in a mechanism constructed as herein shown.

80 I claim—

1. A firearm including a support, a barrel pivotally mounted upon the support, a case movably mounted on the support, means to hold the case against backward movement, the pivot of the barrel and said holding means being relatively arranged to cause disengaging movement by reason of the inherent forces incident to the explosion within the barrel, and means for retaining said holding means in engagement. 85
2. A firearm including a support, a barrel pivotally mounted upon the support to freely swing under the forces caused by an exploding cartridge in the barrel, a case slidably mounted on the support, an interengaging catch upon the barrel and case, said catch being arranged for disengaging movement upon pivotal movement of the barrel, and means for holding the catch in engagement. 95
3. A firearm including a support, a barrel pivotally mounted on the support, a case slidably mounted on the support, a catch upon the case and barrel arranged to be disengaged upon swinging movement of the 105 barrel, said catch being located back of the pivot, and a spring located forward of the pivot to hold the catch in engagement.
4. A firearm including a support, a barrel pivotally mounted on the support, a case 110 slidably mounted on the support, a catch to hold the case against backward movement, said catch being arranged for disengaging movement when the barrel moves upon its pivot, a hammer, means for throwing the hammer forward, and a device connected with said throwing means and with the case to neutralize the force of the former as the case is swung backward. 115
5. In a firearm, a support, a barrel pivotally mounted on the support, a case slidably mounted upon the support, a catch to hold the case against backward movement, said catch being arranged for disengaging action when the barrel swings upon its pivot, a hammer, a spring for throwing the hammer forward, and a device connected with said spring and with the case to neutralize the force of the spring as the case is moved backward. 120

6. A firearm including a support, a pivotally mounted barrel on the support, a case slidably mounted on the support, a catch to hold the case against backward movement, 5 said catch being arranged for disengaging action by reason of swinging movement of the barrel, a hammer, a spring for throwing the hammer forward, and a tensioning lever connected with the spring and with the 10 case.

7. In a firearm, in combination with a hammer, a helical spring located at the side of the hammer with one end engaging the side of the hammer, a tensioning lever connected with the spring, a sliding case, and a connection between the sliding case and tensioning lever.

8. In a firearm, in combination with a hammer, a helical spring having one end 20 engaging the hammer, a tensioning lever engaged with said spring, and means for holding the tensioning lever in a position to release tension of the spring.

9. In a firearm, in combination with a hammer, a helical spring located at the side of the hammer and having one end engaged with the hammer, a tensioning lever pivotally mounted on the frame of the firearm and engaged by the opposite end of said 30 spring, a hammer supporting pin extending through the hammer and having an angular shaped end engaging a similarly formed recess in the lever, the latter having a slot, a sliding case, and a pin upon the sliding 35 case engaging the slot in said lever.

10. A firearm including a support, a barrel pivotally mounted on the support to freely swing upward for unlocking action under the forces caused by an exploding

cartridge in the barrel, a case slidably 40 mounted on the support, means for retaining the case against backward movement, and including means connected with the barrel and operated by its upwardly swinging movement on the support to release said retaining means.

11. A firearm comprising a supporting frame, a firing case mounted on the supporting frame longitudinally slideable thereon and provided with a locking abutment transverse to its sliding action, a barrel mounted on the support movable transversely of the case and provided with a locking abutment engageable by such transverse action with the locking abutment of the case to lock the 55 parts in firing engagement, a hammer mounted on the frame movable in the plane of and by engagement with the case, and an operating spring for actuating the hammer acting between the hammer and the case and 60 compressible by the separating movement of the parts.

12. A firearm including a support, a barrel movably mounted on the support to freely swing upward for unlocking action 65 under the forces caused by an exploding cartridge in the barrel, a member movably mounted on the support, means for retaining said member against movement, and including means connected with the barrel and 70 operated by its upward swinging movement on the support to release said retaining means.

CHARLES J. JOLIDON.
